UNITED STATES PATENT OFFICE.

REGINALD F. SEDGLEY, OF PHILADELPHIA, PENNSYLVANIA.

CLUTCH WRENCH.

Application filed February 28, 1921. Serial No. 447,924.

To all whom it may concern:

Be it known that I, REGINALD F. SEDGLEY, a citizen of the United States, residing in the city and county of Philadelphia, State 5 of Pennsylvania, have invented a new and useful Clutch Wrench, of which the following is a specification.

My invention consists of a novel construction of a clutch wrench which can be cheaply 10 manufactured, is composed of a minimum number of parts, which will be durable and effective and which can be utilized for all the purposes to which a ratchet wrench of a more expensive character is adapted, my 15 novel wrench being so constructed that it may be used for either tightening or loosening nuts, bolts or the like by simply swinging the wrench handle back and forth through relatively small arcs, provision being made for the automatic or manual separation or unlocking of certain of the parts at the proper periods during the actuation of said handle, in order to effect the actuation 20 of the wrench or wrench socket to the desired extent. My invention in its broad and generic scope comprehends a novel construction of a clutch wrench wherein I employ two relatively rotatable members which are adapted to interlock with each other to 25 prevent relative rotation in either direction, one of the members being adapted to receive a device to effect its rotation and the other of said members being adapted to receive or be connected with the part which is to be 30 rotated. A spring is preferably employed to effect the movement of one of the members to cause the member to become unlocked but this can be dispensed with if desired and this unlocking action is effected 35 manually by the actuation of the member which drives the other member.

My invention further consists of a novel construction of a clutch wrench, adapted for all the uses of a more expensive ratchet 45 wrench, wherein I employ a plurality of members which are normally held out of engagement or unlocked by a spring or the like, but which are provided with juxtaposed interlocking faces adapted to be pressed into 50 engagement or into locked position, when desired, according to the direction in which it is desired to oscillate the wrench handle.

It further consists of other novel features of construction, all as will be hereinafter 55 fully set forth.

For the purpose of illustrating my in-

vention, I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a vertical sectional view of a clutch wrench, embodying my invention, certain of the parts being shown in elevation.

Figure 2 represents a perspective view of the outer casing of the wrench seen in Figure 1.

Figure 3 represents a perspective view of the upper actuating sleeve, the spring and the lower plug detached from their casing, showing the manner of assembling these elements.

Figure 4 represents a vertical sectional view of another embodiment of my invention.

Figure 5 represents a perspective view of the actuating sleeve and the lower coacting member in detached position.

Figure 6 represents in detached position a perspective view of the pair of disks and spring employed in Fig. 4.

Figure 7 represents a side elevation, partly in section, of the wrench socket, seen in Figure 1.

Figure 8 represents a side elevation, partly in section, of another embodiment of my invention.

Figure 9 represents a side elevation of another embodiment of my invention.

Figure 10 represents a vertical sectional view of Figure 9.

Similar numerals of reference indicate corresponding parts in the figures.

Referring to the drawings:

1 designates my novel construction of wrench, the same comprising the handle portion 2, which is composed of the straight member 3 and the bent or deflected portion 4, having the abutments or upset portions 5, which limit the extent of movement of the handle terminal 6 with respect to the sliding actuating sleeve 7. The handle 2 is preferably of polygonal or hexagonal shape in cross section and its lower terminal 6 is adapted for insertion into the polygonal or

hexagonal opening 8 which extends through the actuating sleeve 7, as will be understood from Figures 1 and 3.

The actuating sleeve 7 is composed of the 5 lower cylindrical body portion 9 and the upper cylindrical portion 10 of reduced diameter, whereby the shoulder 11 is formed, which abuts against the inturned upper lip or flange 12 of the casing 13, the latter 10 being milled at its upper and lower portions, if desired, as will be understood from Figure 2.

The lower portion of the polygonal or hexagonal opening 8 of the sleeve 7 is adapted 15 to engage the similarly shaped top portion or head 14 of the plug 15, which has the lower cylindrical portion 16 of preferably the same diameter as the cylindrical portion 9, said plug 15 being secured in the bore of 20 the casing 13 by means of the screws or other fastening devices 17. The spring 18 which is contained within the bore of the casing 13 normally causes the actuating sleeve 7 to assume the position seen in Figure 1, it being 25 apparent that a downward pressure on the handle 3 will cause the parts 8 and 14 to interlock, so that when the handle 3 is oscillated in either direction, the actuating sleeve 7, the plug 15 and the casing 13 are 30 rotated or oscillated as a unit. The bottom of the plug 15 has a seat 19 therein of polygonal or hexagonal contour, which is adapted to engage the polygonal head or upward extension 20 of the socket 21, the latter 35 having the seat 22 in the bottom thereof, which is adapted to engage the nut or bolt head, which it is desired to turn. The construction of the socket seen at the bottom of Figure 1, will be readily understood from 40 Figure 7, said socket being provided with the spring pressed spring 40.

It will be seen from the foregoing, that the parts normally appear as seen in Figure 1, or in unlocked position and that if the 45 handle 3 is oscillated in either direction, no rotation will be imparted to the plug 15, the casing 13 or the socket 21.

If, however, downward pressure is exerted upon the handle 3 and the actuating 50 sleeve 7 against the tension of the intermediate spring 18, the lower portion of the polygonal seat 8 will interlock with the polygonal extension 14, whereupon the handle 3, the sleeve 7, casing 13, plug 15 and 55 socket 21 can be turned as a unit in the desired direction, and the nut or the like rotated to the desired extent. Upon removing the pressure from the handle 3, the parts again assume the unlocked position seen in Figure 60 1, whereupon the handle 3 can be oscillated in the desired direction, then pressed downwardly and the parts again interlocked, so that further rotation in the desired direction may be imparted to the socket 21.

65 In the construction seen in Figures 4 to 6,

I have shown the casing 23 as provided with the actuating sleeve 24, which has a polygonal or hexagonal opening 25 for the insertion of the terminal 6 of the handle, said sleeve 24 being retained in position within 70 the casing by the ring 26, which contacts with the shoulder 27 formed at the junction of the cylindrical portions 28 and 29 as will be understood from Figure 5. The bottom periphery of the cylindrical portion 29 of the sleeve 24 is provided with the teeth 30, which are adapted at the proper intervals 75 to mesh or interlock with the teeth 31 of the socket member 32, the latter having the polygonal or hexagonal opening 33 therethrough.

The upper portion of the member 32 has a disk 34 seated therein, upon which rests the bottom end of the spring 35, the upper end of the said spring contacting with disk 36, said disks 36 and 34 seating on shoulders in the operating sleeve 34 and the member 32, as will be understood from Figure 4. The member 32 is immovably secured with respect to its enclosing casing 33 by means of the screws or similar fastening devices 37, as will be understood from Figure 4.

The object of the provision of the ratchet teeth 30, 31 is to enable the clutch wrench, seen in Figures 4 to 6 to be used as a ratchet wrench in somewhat closer quarters and for finer adjustments than the wrench seen in Figure 1 might be adapted to, and its mode of operation will be understood from the description of Figure 1, the locking and unlocking of the teeth 30 and 31, enabling the wrench to have the same function as the locking and unlocking of the equivalent elements 8 and 14 seen in Figure 1.

In the construction seen in Figure 8, I have shown the handle 41, as being provided at its opposite end with a polygonal or hexagonal hole 42 therethrough, which is adapted to engage the polygonal or hexagonal end 43 of the stem 44, the latter having the upward extension 45 of reduced diameter, which terminates in the head 46, there being a spring 47 interposed between said head 46 and the upper portion of the stem 44, the lower portion of which terminates in the socket member 48.

In the construction seen in Figures 9 and 10, I have shown another embodiment of my invention, the outer casing being designated as 49 and the polygonal or hexagonal member 50 having a driving fit through the upper or top wall 51 thereof.

52 designates a sleeve slidably mounted in the lower portion of the bore of the casing 49 and held therein by the bottom inwardly turned flange or lip 53, said sleeve having a polygonal or hexagonal socket 54 therein and its upper portion being engaged by the spring 55 whose upper end abuts 125 against the wall 56, said spring surrounding 130

the downward polygonal extension 57, which is of the same contour as the polygonal hole 54. departing from the spirit or scope of the invention or sacrificing any of its advantages. 85

Having thus described my invention, what I claim as new and desire to secure by Letters Patent, is:—

- 5 1. In a clutch wrench, a casing, a member having a polygonal surface, fixedly secured in said casing, a member rotatably mounted in said casing and having a polygonal hole therein adapted to be engaged by said polygonal surface and a spring contained in said casing and normally holding said members apart said members being incapable of relative rotation when interlocked and said rotatable member having means to receive and interlock with an actuating member. 70
- 10 2. In a clutch wrench, a rotatable actuating sleeve having a polygonal opening therethrough a casing in which said sleeve is mounted, a plug fixedly secured in said casing and having an upper polygonal head aligning with said polygonal opening and a spring between said sleeve and plug. 75
- 15 3. In a clutch wrench, a casing, a rotatable actuating sleeve therein having teeth on its lower periphery and a polygonal hole therethrough, a lower member having a polygonal hole therethrough, fixedly secured in said sleeve and having teeth on its upper periphery, juxtaposed to the teeth in said sleeve, disks seated in said sleeve and lower member and a spring interposed between said disks. 80
- 20 4. In a clutch wrench, a casing, a polygonal member secured in the top thereof, and having an upward and downward polygonal extension, a sleeve rotatably mounted in said casing, and having a polygonal opening therethrough aligning with said downward extension and a spring intermediate said downward extension and sleeve. 85
- 25 5. In a clutch wrench, a casing, a rotatable sleeve in its lower portion having a hexagonal opening therethrough, said casing having an inwardly deflected bottom flange to retain said sleeve in position, a hexagonal member secured in the top of said casing and having a downward extension aligning with the opening in said sleeve, and a spring located between said sleeve and the top of said casing. 90
- 30 6. In a clutch wrench, a casing, a member free to rotate with respect to said casing, a member fixed to said casing and adapted to interlock with said rotatable member to prevent relative rotary movement of said members in either direction, one of said members having a polygonally shaped opening adapted to receive a working tool and the other of said members being adapted to receive and interlock with an actuating member, and a spring to effect relative movement of said members to unlock them, 95
- 35 7. In a clutch wrench, a casing, a polygonal member secured in the top thereof, and having an upward and downward polygonal extension, a sleeve rotatably mounted in said casing, and having a polygonal opening therethrough aligning with said downward extension and a spring intermediate said downward extension and sleeve. 100
- 40 8. In a clutch wrench, a casing, a polygonal member secured in the top thereof, and having an upward and downward polygonal extension, a sleeve rotatably mounted in said casing, and having a polygonal opening therethrough aligning with said downward extension and a spring intermediate said downward extension and sleeve. 105
- 45 9. In a clutch wrench, a casing, a rotatable sleeve in its lower portion having a hexagonal opening therethrough, said casing having an inwardly deflected bottom flange to retain said sleeve in position, a hexagonal member secured in the top of said casing and having a downward extension aligning with the opening in said sleeve, and a spring located between said sleeve and the top of said casing. 110
- 50 10. In a clutch wrench, a casing, a rotatable sleeve in its lower portion having a hexagonal opening therethrough, said casing having an inwardly deflected bottom flange to retain said sleeve in position, a hexagonal member secured in the top of said casing and having a downward extension aligning with the opening in said sleeve, and a spring located between said sleeve and the top of said casing. 115
- 55 11. In a clutch wrench, a casing, a rotatable sleeve in its lower portion having a hexagonal opening therethrough, said casing having an inwardly deflected bottom flange to retain said sleeve in position, a hexagonal member secured in the top of said casing and having a downward extension aligning with the opening in said sleeve, and a spring located between said sleeve and the top of said casing. 120
- 60 12. In a clutch wrench, a casing, a rotatable sleeve in its lower portion having a hexagonal opening therethrough, said casing having an inwardly deflected bottom flange to retain said sleeve in position, a hexagonal member secured in the top of said casing and having a downward extension aligning with the opening in said sleeve, and a spring located between said sleeve and the top of said casing. 125

said members when locked rotating as a unit.

7. In a clutch wrench, a casing, a member free to rotate with respect to said casing, a member fixed to said casing and adapted to interlock with said rotatable member to prevent relative rotary movement of said members in either direction, both of said members being adapted to receive

working tools, and a spring to effect relative movement of said members to unlock them, said members when locked rotating as a unit.
